(57) **CLAIM**

The ornamental design for a shelf organizing system, as shown and described.

DESCRIPTION

FIG. 1 is an exploded front perspective view of a shelf organizing system, showing my new design;

FIG. 2 is a side elevational view thereof;

FIG. 3 is an exploded top view thereof;

FIG. 4 is a front elevational view thereof; and,

FIG. 5 is a front perspective view thereof.

The broken line showing in the drawings represents environmental structure and forms no part of the claimed design.
